UNITED STATES PATENT OFFICE.

HERMAN DAVIS, OF SHEBOYGAN, WISCONSIN.

TRUNK.

Application filed December 2, 1922. Serial No. 604,599.

To all whom it may concern:

Be it known that I, HERMAN DAVIS, citizen of the United States, residing at Sheboygan, in the county of Sheboygan and 5 State of Wisconsin, have invented new and useful Improvements in Trunks, of which the following is a specification.

My present invention pertains to trunks and it contemplates the provision of a trunk 10 of the ordinary or "old style" type that may be readily converted and used after the manner of the wardrobe trunk with but a slight amount of effort on the part of those using the trunk.

15 The invention further contemplates the provision in a trunk of a wardrobe tray that is adapted to be swung or otherwise moved to a vertical position with respect to the body portion of the trunk at one end thereof and notwithstanding its hinging ability is adapted to be entirely removed 20 from the body portion without the manipulation of levers or other elements.

25 The invention further contemplates the provision of a tray that is adapted to be removed from the body portion of the trunk with the clothes hanging therein and placed or otherwise secured in a closet and be used as a wardrobe and the body of the trunk can 30 be used after the manner of the old style box trunk.

35 The invention in all of its details will be fully understood from the following description and claims, when the same are read in connection with the drawings, accompanying and forming part of this specification, in which:

Figure 1 is a perspective view of the trunk and showing a portion thereof cut-away.

40 Figure 2 is a transverse sectional view of the trunk and showing the tray arranged therein.

45 Figure 3 is a sectional view illustrating the tray in its normal position outside one end wall of the trunk.

Figure 4 is an inverted plan view of the tray.

Figure 5 is a sectional view of the trunk and tray thereof.

50 Similar numerals of reference designate corresponding parts in all of the views of the drawings.

My trunk comprises the body portion 1 that is of the ordinary well known type and 55 the said body is adapted to receive therein a tray 3 that in the construction illustrated

is provided with a rest board 5 that forms a portion of the end wall 2 of the trunk when the tray is in the position shown in Figure 1 and forms a rest for the tray when the 60 said tray is in the position shown in Figure 3. At this point I would distinctly have it understood that the end wall 2 may have a cut-away portion that is closed by the board 5, or the said board may be hinged to 65 the portion 2 of the end wall and then again this board may be separate and distinct from the bottom or end of the tray when desired and separately removable from the end wall and portion 2. I make this provision for 70 the reason that experience has taught that sometimes, it is desirable to have the portion 5 form with the portion 2 a hinged end wall; sometimes it is desirable that the board 5 be entirely removed and then again it occurs 75 that this board is highly desirable as permanently secured to the end of the tray. The construction shown is therefore merely for the purposes of illustration.

As is the well known practice most trunks 80 are provided with the rail 4 to bear the ends or edges of the lower surface of the tray and secured to the underside of the tray as shown in a series of feet 6 that may be of the construction illustrated or of any 85 construction compatible with their purpose. These feet 6 are secured to the tray at the underside and near the inner end when the tray is normally resting in the trunk and at the forward end I provide the feet or fixtures 90 95 7 that are not only provided with a surface that travels in the track 8 that is secured in the trunk, but are further formed with a hooked end that enters the opening 8a of said track 8 and prevents casual displacement of the tray from the trunk when said tray assumes the position shown in Figure 3. However, the said hooked end of the fixture 7 will not preclude the lifting of the tray from the track and the entire removal 100 of the tray from the trunk.

At this point I would distinctly have it understood that the fixture illustrated is shown merely for the purpose of illustration as the purpose of the invention is to provide any style fixture that will permit hinging of the tray with respect to the trunk and at the same time will enable a person to entirely remove the tray from the trunk. In other words the construction of fixture is 110 such as to include in an old style trunk a wardrobe tray and removable tray.

From the description so far it will be manifest that the tray under normal conditions will rest with its inner wall 3^a on the rail 4 and the feet or fixtures in the U-shaped tracks or channels 8 and when the tray is moved to the left the fixture 7 will fall into the aperture 8^a of rail 8 and cause the tray to assume the position shown in Figure 3. Experience has proven that frequently it is necessary for the tray to be hung, rest and slide on the upper edge of the walls of body 1 and sometimes it is better to have the tray 3 rest on a lower tray or a partition in the bottom of body 1. Again a series of sticks or rods may be fastened to the inner side walls of body 1 for tray 3 to rest or slide on.

The trunk is provided with the hinged lid 9 and within the lid I prefer to provide the follower board 9^a which is provided with the springs 9^b to compress the articles within the trunk when the lid is closed. The lid is also provided with the side walls 10 and the tray is also provided with the re-enforcing plate 3^b on the end wall 3^a and in the lower wall of the tray I provide hanger openings 11.

It will be manifest that the tray is adapted to be entirely removed and hung on nails or other means by passing said means through the openings 11 of said tray. When desired the trunk may be employed with the tray after the manner of a wardrobe trunk and without the tray after the manner of an old style well known packing or dress trunk.

It is apparent that the trunk is extremely inexpensive to produce and manipulate and comprises no delicate parts such as are liable to wear out after a short usage and the tilting and lifting of the tray from the trunk is a matter of practically no moment.

Having described my invention, what I claim and desire to secure by Letters Patent, is:

1. In a trunk the combination of a body portion, a wall hinged to one end of the body, tracks formed in the body portion and having an aperture near one end thereof, a tray having hooks secured to the underside thereof and adapted to normally rest in the tracks and being so constructed and arranged to drop into the apertures of the tracks to act as a pivot when the tray is thrown into vertical position with respect to body of the trunk.

2. In a trunk, the combination of a body portion having one hinged end wall, tracks having a channel and an aperture at the ends thereof, a tray adapted to rest on the tracks, fixtures constructed to travel in the tracks and having a bent portion whereby when the tray is moved along the tracks the fixtures will fall into the apertures of the tracks and act as a pivot during swinging of the tray to a vertical position with respect to the body portion.

3. In a trunk, the combination of a body portion having one side wall thereof hinged, a track formed in the body portion and having an aperture near one end thereof, a tray having fixtures secured to the underside thereof and adapted to rest in the track and enter the aperture to hinge the tray with respect to the track and also being adapted to permit of removal of the tray from the body portion.

In testimony whereof I have hereunto set my hand in presence of two subscribing witnesses.

HERMAN DAVIS.

Witnesses:
